Primary Examiner — Marissa J. Cash*Assistant Examiner* — Kayla Marie Bennett*(74) Attorney, Agent, or Firm* — Hoang Steve Ngo(57) **CLAIM**

The ornamental design for a device for drying painting tools, as shown and described.

DESCRIPTION

FIG. 1 is a front view of a device for drying painting tools; FIG. 2 is a rear view of the device for drying painting tools of FIG. 1;

FIG. 3 is a left side view of the device for drying painting tools of FIG. 1;

FIG. 4 is a right side view of the device for drying painting tools of FIG. 1;

FIG. 5 is a top view of the device for drying painting tools of FIG. 1;

FIG. 6 is a bottom view of the device for drying painting tools of FIG. 1; and,

FIG. 7 is a perspective, front view thereof, shown in an environment of use.

The broken lines shown in FIG. 7 are for purposes of illustrating environmental subject matter only and forms no part of the claimed design.

1 Claim, 6 Drawing Sheets(56)
